UNITED STATES PATENT OFFICE.

PLEASANT T. BROCK, OF TROY, IDAHO.

COW-TAIL HOLDER.

SPECIFICATION forming part of Letters Patent No. 653,336, dated July 10, 1900.

Application filed May 8, 1900. Serial No. 15,908. (No model.)

To all whom it may concern:

Be it known that I, PLEASANT T. BROCK, a citizen of the United States, residing at Troy, in the county of Latah and State of Idaho, 5 have invented a new and useful Cow-Tail Holder, of which the following is a specification.

This invention relates to cow-tail holders, and has for its object to provide an improved device of this character which may be conveniently applied to a cow to hold the tail thereof while the cow is being milked. It is furthermore designed to prevent the cow from switching or flirting her tail toward the 15 milker, while at the same time permitting of the tail being switched in the opposite direction in order that the cow may scare away flies and insects without interfering with the milker.

With these and other objects in view the present invention consists in the combination and arrangement of parts, as will be herein-after more fully described, shown in the accompanying drawings, and particularly set 25 forth in the appended claims, it being understood that changes in the form, proportion, size, and minor details may be made within the scope of the claims without departing from the spirit or sacrificing any of the advantages of the invention.

In the drawings, Figure 1 is a perspective view illustrating the application of the present invention. Fig. 2 is a detail perspective view of a cow-tail holder constructed in accordance with the present invention. Fig. 3 is a detail sectional view illustrating the manner of connecting the tail-engaging clamp to the suspending harness.

Corresponding parts in the figures of the drawings are designated by like characters of reference.

Referring to the drawings, and particularly to Fig. 2 thereof, it will be seen that the present device comprises a harness formed by a 45 back-strap 1, which normally assumes an inverted-U shape, having the rings 2 at the opposite ends thereof. Connected to the opposite rings is a horizontally-disposed substantially U-shaped or looped hip-strap 3, 50 the opposite ends of which are provided with buckles 4, so as to form loops to embrace the respective rings 2, and thus form an adjust-

able connection between the hip and back straps.

Secured at a point midway between the opposite ends of the back-strap is a lateral rearwardly-directed leather loop 5, which embraces a ring or link 6, and from this ring depend the divergent supporting-straps 7, that have their lower ends riveted or otherwise 60 connected to the respective opposite sides of the hip-strap, as at 8, and near the outer or rear end thereof, while the upper ends thereof are provided with the buckles 9, so as to form loops for engagement with the ring 6, and 65 thus provide an adjustable connection with the back-strap.

At the bend or rear end of the hip-strap and intermediate of the suspending-straps 7 there is provided a tail-engaging clamp 10, which 70 is in the form of a hook, which projects forwardly from the inner side of the hip-strap. This clamp is preferably formed from a single length of heavy wire, which is bent intermediate of its ends into a loop-shaped hook, 75 and then the opposite portions of the wire are brought together, so as to form a straight shank 11, which lies flat against the outer side of the hip-strap, as best shown in Fig. 3. The bend between the shank and the hook 80 proper is received through an opening 12 in the hip-strap, and the opposite end of the shank is passed through an opening in the strap and clenched or upset, as at 13, against the inner side of the strap.

In the application of the device, as shown in Fig. 1 of the drawings, it will be seen that the back-strap is placed transversely across the back of the animal, so as to lie immediately in front of the hips thereof, with the 90 hip-strap embracing the hips of the animal and the tail thereof. It will now be seen that the tail is received or embraced by the clamp or hook 10, so as to effectively prevent the tail from being switched in one direction, 95 while it is free to be moved in the opposite direction, whereby the milker is not annoyed by the switching of the tail, and the latter may be switched upon the opposite side of the cow to scare away flies and other insects. 100 The hook or clamp is preferably located slightly to one side of the middle of the hip-strap and adjacent to the milker, so that the tail may normally remain in its usual posi-

tion. Furthermore, the opening of the hook or clamp is turned away from the milker, so that the tail is held against movement toward the milker and is free to move in the opposite direction.

From the foregoing description it is apparent that the present device provides a simple and effective cow-tail holder, which is arranged for convenient application and removal and may be readily adjusted to animals of different sizes.

What is claimed is—

1. A cow-tail holder, comprising a harness to be supported upon the cow, and a tail-engaging device, which embraces one side only of the tail and is located upon the inner side of the harness.
2. A cow-tail holder, comprising a harness to be supported upon a cow, and a hook located upon the inner side of the harness and

forming a tail-engaging device, which embraces one side only of the tail.

3. A cow-tail holder, comprising a harness for application to an animal, and a tail-engaging device located upon the inner side of the harness and formed from a single length of wire bent intermediate of its ends into a loop-shaped hook, the opposite end portions being brought together into a shank, the opposite ends of which are passed through openings in a portion of the harness, the outer end of the shank being upset against said harness.

In testimony that I claim the foregoing as my own I have hereto affixed my signature in the presence of two witnesses.

PLEASANT T. BROCK.
